UNITED STATES PATENT OFFICE

CHARLES C. BLACKMORE, OF DAYTON, OHIO

SAFETY RAZOR

Application filed October 24, 1928. Serial No. 314,766.

The object of this invention is to provide a safety razor in which the parts are few and compactly related to each other.

It is also an object of this invention to provide a safety razor in which the blade part is composed of either a continuous strip of blade material or a similar strip attached at its end to two rollers and adapted to be adjusted in such a way that the cutting edge 10 of the blade may be advanced so a fresh edge will come into use.

It is an object also of this invention to provide a device of this kind, in which the blade strip is detachably supported and may be 15 readily removed from a supporting case. It is a further object of this invention to provide a razor of this type and such size that it can be conveniently carried in a vest pocket, or some similar place.

It is particularly an object of this invention to provide a razor of this type in which the parts are so arranged that the operation of the blade is positive and certain, and that the blade at all times is in the position for 25 service.

It is also an object of this invention to provide, in connection with a case supporting the razor blade, suitable means to assist in restoring and preserving the edge of the 30 blade.

In the accompanying drawings there are shown preferred forms of this invention, which are used by way of illustration alone, applicant not desiring to be limited by the 35 particular form of safety razor here shown.

In the drawings:

Figure 1 is a top plan view of the razor casing showing in dotted lines the blade and the blade supporting parts.

Figure 2 is a front elevation showing the cutting blade and the protecting teeth therefor.

Figure 3 is a cross section on the line 3—3 of Figure 1.

Figure 4 is a sectional view through the blade and the casing, showing the blade and the blade operating parts.

Figure 5 is a view of the blade used in connection with the form shown in Figures 50 1 and 4.

Figure 6 is a top plan view showing a modified form of blade strip.

Figure 7 is a front elevation of the form shown in Figure 6.

Figure 8 is a cross section on the line 8—8 55 of Figure 6.

Figure 9 is a section showing the means by which the razor blade is supported and operated.

In the two different modifications of the 60 safety razor shown in the drawings, the casing is identical in each case, the only difference being the blade structure and the manner of supporting and operating the blade. In one the blade is continuous, while in the 65 other each end of the blade is attached to a roller, by which the blade is operated.

The outer part of the safety razor is composed of a casing consisting essentially of 70 two cover members, one indicated by the numeral 1 and the other indicated by the numeral 2, which are pivoted together, as indicated by the numeral 3. When the two parts are hinged together, as indicated in Figures 1 and 6, the casing is substantially rectangular, having along one side thereof the hinge section, while along the opposite edge is located the razor blade and its operating parts.

Extending from the cover member 1 is a 75 handle 4. This handle is used for manipulating the razor, and is to be gripped by the hand when in use.

The outer end of each of the cover members 1 and 2 is bent toward the other. The bent part of cover 1 is indicated by the numeral 5 and merely forms an end support for that part of the blade used for shaving purposes, and consists essentially of two lip members used for that purpose. The bent part of the cover member 2 is indicated by the numeral 6, and is in the form of a series of teeth which fit directly over the blade when in use and protect the face of the user from being cut by the razor. The number of these teeth can be arranged to suit any convenient demand, and may be small or larger, further apart or closer together.

Located on the side of the casing, opposite the hinge, there are two or more wheel members 7. In the present instance there are two 100

of these wheels shown. Any number that is desired or necessary could be used. On the outer circumference of these wheels there is a series of radially arranged pins 8. Each of these wheels is supported in suitable bearings in the cover members 1 and 2, and may be removed and replaced for the purpose of adjusting thereon the razor blade, to be described later on. Each of these wheels has 19 axle members 9, adapted to rotate in suitable bearings formed in the cover members, indicated by the numeral 10.

For the purpose of rotating one or more of these rollers there is provided a key member 11, which is pivotally attached to one of the axle members 9, as indicated by the numeral 12.

For the purpose of sharpening the razor strip and removing any foreign matter that 20 might accumulate, and to aid in giving a smooth surface to the blade, there are provided two rollers 13, which have a rough honing face, and two other rollers 14, which have a smoothing surface. These rollers are arranged on opposite sides of the blade, and as the blade is operated it passes between the rollers. The first roller tends to sharpen it with a more or less rough edge, while the latter two rollers give it a smoother finish and 30 a smoother edge.

The blade part consists of a continuous strip of razor blade material 15, and has along the central part thereof a series of holes 16, which are adapted to engage the pins 8 on 35 the rollers or wheels. By this means, as the rollers are rotated, the blade is advanced or shifted. The purpose of this advancement of the blade is to be able to remove that part of the blade that has become dull and to advance 40 a part of it that is keen and ready for shaving purposes. The blade is advanced or shifted in such a manner as to cause the inside part of the blade to advance or shift through the sharpening rollers first, and then through 45 the leather or smooth faced rollers second.

In Figures 6, 7, 8 and 9 are shown modified forms of this razor, in which the ends of the blade strip are attached to the rollers instead of the strip being continuous. The 50 razor strip is attached to the roller in a manner indicated by the numeral 7' of Figure 6. This blade may be advanced or shifted one way as far as the rollers will permit it, and then advanced or shifted in the other direction until the complete, or practically the 55 complete razor blade is taken up on the first roller. These blades can be sharpened by removing them, or by applying to them as they are fitted in the casing, some sharpening 60 tool.

The blade in this form is indicated by the numeral 15', which is attached to the rollers in the manner indicated above. For the purpose of operating the rollers to adjust the 65 blade there is a key member similar to that

shown in the other form, and indicated by the numeral 11. This key member is adapted to fit in a socket in the shafts which carry the rollers, and may be applied to either one of the rollers as preferred.

The parts of the casing, composed of cover members 1 and 2, may be suitably locked in closed position by any means convenient. If the members 1 and 2 are not to be opened the spindle upon which the rollers are fastened 75 may be permanently attached to the covers 1 and 2 so that the covers can not be opened but are held in permanent relation to each other, however permitting the roller to rotate in proper bearings in the cover members. 80

I desire to comprehend within my invention such modifications as may be clearly embraced within my claims and the scope of my invention.

Having thus fully described my invention, 85 what I claim is new and desire to secure by Letters Patent, is:

1. In a safety razor, a casing formed of two pivotally connected side members, rollers 90 removably and adjustably supported by said casing, a continuous blade member carried by said rollers, and means on the casing for rotating the rollers to shift the blade and a pair of blade supports on one side member and a series of teeth on the other member extending over the blade.

2. In a safety razor, a casing formed of two pivotally connected side members, rollers carried by said casing, a razor blade strip carried by said rollers, and key means to rotate the rollers to shift the blade, and supporting and protecting means for said blade on 100 said side members.

3. In a safety razor, a casing composed of a pair of side members pivotally connected along one edge, a plurality of rollers removably carried by said casing, and a razor blade strip carried by said rollers.

4. In a safety razor, a casing formed of pivotally connected side members, a pair of rollers supported by said casing, said rollers having radially extending pins thereon, a continuous strip razor blade carried by said rollers engaged by said pins, and means associated with said rollers to rotate the rollers to shift said strip and a pair of blade supports extending from one of said members.

5. In a safety razor, a rectangular casing composed of a pair of pivotally connected side members having a handle thereon, a blade detachably carried by said casing, said blade being formed of one continuous strip of blade material, means for supporting the blade in the casing and adapted to shift the blade with respect to the casing, and sharpening means adapted to sharpen said blade when moved.

6. In a safety razor, a casing, a flexible blade strip, rollers in said casing for supporting and shifting said blade, and a pair of 130

honing rollers engaging said blade as the blade is shifted by said supporting rollers.

7. In a safety razor, a casing, a pair of rollers supported by said casing, a flexible blade strip supported and shifted by said rollers, a pair of rough honing rollers engaging opposite faces of said blade, and a pair of smooth honing rollers engaging opposite faces of said blade.

10 8. In a safety razor, a casing composed of a pair of pivotally connected cover members, a pair of rollers supported by said casing, a flexible blade strip supported and shifted by said rollers, a pair of rough honing rollers supported by said casing and engaging opposite faces of said blade, all of said rollers being adapted to be removed from said casing when the cover members are opened out.

9. In a safety razor, a casing formed of side members pivotally connected along one edge thereof, a flexible continuous razor blade carried by said casing, a pair of blade supports extending from one of said members and engaging one side of said blade, and a plurality of teeth extending from the other of said side members and engaging the other side of said blade opposite said supports.

10. In a safety razor, a casing formed of rectangular side members pivotally connected along one of the edges thereof, and a flexible continuous razor blade carried by said casing and adapted to travel along the edge of the casing opposite the pivotal connection of the side members.

35 11. In a safety razor, a casing formed of rectangular side members pivotally connected along one of the edges thereof, a flexible continuous razor blade carried by said casing and adapted to travel along the edge of said casing opposite the pivotal connection of the side members, a support member for said blade at each end of the edge of the casing opposite the pivotal connection, and extending from one of said side members, 40 and a plurality of teeth extending from the other of said side members and over the blade opposite said supports.

In testimony whereof, I affix my signature.
CHARLES C. BLACKMORE.
